UNITED STATES PATENT OFFICE.

EUGEN WOERNER, OF STUTTGART, GERMANY, ASSIGNOR TO THE FIRM OF ROBERT BOSCH, OF STUTTGART, GERMANY.

FORCE-PUMP MECHANISM.

1,225,911.

Specification of Letters Patent.

Patented May 15, 1917.

Application filed July 14, 1914. Serial No. 850,957.

To all whom it may concern:

Be it known that I, EUGEN WOERNER, a subject of the Emperor of Germany, residing at Lerchenstrasse 28, Stuttgart, Germany, have invented certain new and useful Improvements in Force-Pump Mechanism; and I do hereby declare the following to be a full, clear, and exact description of the invention, such as will enable others skilled in the art to which it appertains to make and use the same.

In lubricating certain kinds of machinery, like steam engines and internal combustion engines for example, it is necessary to force oil under high pressure into certain parts, such as the cylinder, whereas oil may be supplied at low pressure to certain other parts, such as the main bearings. Furthermore, the quantity of high pressure oil required is usually small compared with the quantity of low pressure oil, and the latter sometimes flows in a continuous circuit from the pump to the parts to be lubricated, and then into the crank case of the engine, from where it is sucked up by the low pressure pump, while the high pressure oil does not return to the pump. Inasmuch as the requirements are so different, it has heretofore been customary for automobiles, motor boats and like installations to provide two independent lubricating systems with individual driving mechanisms therefor, the high pressure pumps capable of developing a pressure of fifty atmospheres or more having a small cylinder bore, and being single acting, and the low pressure pumps capable of developing but 0.5 atmosphere having a comparatively large cylinder bore and being double acting.

The object of the present invention is to consolidate the high and low pressure lubricating pumps into a single apparatus having a common drive, thereby simplifying the installation and reducing the space and cost. I attain this object in the preferred form of construction by disposing one or more high pressure piston pumps, and one or more low pressure piston pumps, around a common driving shaft, and so constructing the driving connections of the pistons of the pumps and

the driving connections of the pistons of the controlling valves therefor, that a single cam on the shaft engages the driving connections of all the pump pistons in one circle to reciprocate them in order, while a second cam on the shaft engages all the driving connections of the controlling valve pistons in a concentric circle to reciprocate them in proper time relation. As a further result of this arrangement, one or more of the high pressure pumps may be used to supply a quantity of oil from its source directly to the crank case of the engine, from which the low pressure pump or pumps take their supply, to thereby compensate for the quantity of oil that is used up in the main bearings and the other part through which the low pressure oil circulates.

In the accompanying drawings, illustrating as an example this preferred embodiment within my invention,

Figure 1 represents an elevation of the pump mechanism with the casing in section;

Fig. 2 represents a section on line 2—2 of Fig. 1; and Figs. 3, 4 and 5 represent, to an enlarged scale, some of the details of the low pressure pump and the controlling valve mechanism therefor.

The base plate *b* is suspended in the oil receptacle *a* by means of the posts *d* which are fastened to the cover *c*. The single acting high pressure pumps *e'*, *e²*, *e³*, etc., of the desired number and of the well known kind are fastened on the base plate and have their pistons *r* with the driving connections therefor in the form of yokes *y* disposed in circular arrangement about the axis of the driving shaft *f* as a center. The pistons *r'* of the controlling valves of the high pressure pumps have driving connections in the form of notches *y'* and are disposed in a circle concentric with the other circle. Although more may be provided, the drawings show one low pressure pump *k* of the well known double acting type. The piston *s* of this pump having a driving connection therefor, in the form of a yoke *m* similar to the other yokes *y*, is disposed in the same circle as the high pressure pistons *r*. Inasmuch as the cylinder bore of the low

pressure pump h is large compared with that of the high pressure pumps, the pistons s of the controlling valves are arranged inside of the circle passing through the controlling valve pistons r' , but each is provided with a driving connection in the form of a deep yoke m' extending for driving engagement into said circle. The driving shaft f is journaled through the base plate b and is driven by the worm gearing g . The inclined cam disk h is fastened on the shaft and extends within the yokes y of the high pressure pumps and also within the yoke m of the low pressure pump, so as to have driving engagement with all of the high and low pressure pumps to reciprocate the pistons in order. Likewise, the cam disk i is fastened on the driving shaft and extends into the notches y' and also into the yokes n' , so as to have driving engagement with all of the controlling valves of the high and low pressure pumps to reciprocate the pistons thereof in proper time relation with respect to the pump pistons.

If the radial distance between the centers of the pistons r and r' of the high pressure pumps be denoted by p_1 , and if the corresponding radial distance for the low pressure pump be denoted by p_2 , then the depth of either yoke m beyond the center of the corresponding piston s' is $l = p_2 - p_1$. Obviously, the same result would be attained by locating the controlling valve pistons s' in the circle of the controlling valve pistons r' and then arranging the piston s of the low pressure pump outside of the circle of the pistons r of the high pressure pumps by the distance l ; or by offsetting the pistons s' as well as the piston s by distances equal in the aggregate to the distance l . In all of these cases, however, the driving connections of the offset pistons must have the proper driving engagement with the cam disk. It is also apparent that the high pressure pumps may be double acting, or that the low pressure pump may be single acting, if desired.

The operation of the consolidated pump mechanism hereinbefore described is as follows: During rotation of the driving shaft f , the high-pressure pump pistons r , and also the low-pressure pump pistons s are reciprocated by reason of the driving engagement between the actuating surfaces of the cam disk h and the contact surfaces of the yoke driving connections y and m ; and similarly the controlling valve pistons r' and s' are then reciprocated by reason of the driving engagement between the actuating surfaces of the cam disk i and the contact surfaces y' and m' . The elevated and depressed portions of the cam disks h and i are so arranged that the cycle of the pump pistons is displaced 90° from the cycle of the corresponding valve pistons. Thus

when the low-pressure pump piston s is starting its down stroke, as indicated in Fig. 4, the two valve pistons m' therefor are half way down. As the pump piston makes its down stroke, the two valve pistons move to their lowermost positions and return to their half way positions. During this movement of the pistons, the oil is forced from below the downwardly moving pump piston through the right hand branch of the discharge conduit to the place to be lubricated and oil is simultaneously sucked into the cylinder above the piston through the left hand branch of the inlet conduit as shown by the full line arrows. On the up-stroke of the pump piston, during which the valve pistons move to their uppermost position and then return to their half way positions, the oil is sucked into the cylinder below the pump piston and is forced out of the cylinder from above the piston, as indicated by the dotted arrows. In this way, the low-pressure pump is double-acting and is adapted for discharging large quantities of oil at low pressure to the bearings and other places to be lubricated.

The high pressure pumps are single-acting, and the operation of the valve mechanism therefor may be of any suitable kind, as for instance similar to that shown in United States Patent No. 956,016 of April 26, 1910.

Having thus described my invention, what I claim is:

1. In consolidated high and low pressure pump mechanism, a single-acting high-pressure pump having a pump piston and a valve piston, a double-acting low-pressure pump having a pump piston and two valve pistons, and common driving mechanism for both pumps comprising a rotary shaft, a cam mounted on the shaft in driving engagement with both pump pistons to reciprocate them, and a second cam mounted on the shaft in driving engagement with the valve pistons of both pumps to reciprocate them in suitable relation with the respective pump pistons.

2. In consolidated high and low pressure pump mechanism, a plurality of high-pressure pumps having pump pistons with driving connections disposed in one circle and valve pistons with driving connections disposed in another circle about the same center, a low-pressure pump of large bore having a pump piston with a driving connection located in the circle with the driving connections of the high-pressure pump pistons and also having valve pistons with driving connections extending into the circle of the driving connections of the high-pressure pump pistons, and common driving mechanism for all the pumps comprising a shaft rotatable on an axis passing through the center of said circles, a cam mounted on

the shaft in driving engagement with the driving connections of all the pump pistons to reciprocate them, and a second cam mounted on the shaft in driving engagement

5 with the driving connections of all the valve pistons to reciprocate them in suitable relation with respect to the pump pistons.

Copies of this patent may be obtained for five cents each, by addressing the "Commissioner of Patents, Washington, D. C."

In testimony whereof I affix my signature, in presence of two witnesses.

EUGEN WOERNER.
